UNITED STATES PATENT OFFICE.

JULES LE PAGE, OF DARLINGTON, INDIANA.

CUTTING-ROLLS.

1,183,574.

Specification of Letters Patent.

Patented May 16, 1916.

Application filed February 24, 1916. Serial No. 80,167.

To all whom it may concern:

Be it known that I, JULES LE PAGE, a citizen of the United States, residing at Darlington, in the county of Montgomery and 5 State of Indiana, have invented certain new and useful Improvements in Cutting-Rolls, of which the following is a specification.

My invention relates to the rolls which are used in milling various grains and cereal 10 products, and has especial reference to those processes in which cereals are cleanly cut or broken to produce "cracked" or "steel-cut" products. Heretofore in the preparation of such products a very considerable amount 15 of the material treated has been lost by the crushing or grinding effect of the rolls, and rendered comparatively worthless. By the use of my improvements I am able to avoid practically all of the crushing or 20 grinding action which has been inseparable from the operation of other rolls or machinery in making the products described. And I am thereby able greatly to increase 25 the proportion of cracked or cut material and correspondingly to reduce the proportion of flour or meal which, in this line of manufacture, becomes a by-product.

The principles of my invention are illustrated in the drawings, in which—

30 Figure 1 is a top view of a portion of one pair of my improved rolls; Fig. 2 is a comparatively enlarged end view of the fast moving roll; Fig. 3 is a top view of an enlarged portion of the slow moving roll; Fig. 35 4 is a sectional view of a portion of the two rolls, as shown in Figs. 2 and 3, the fast moving one being in modified form.

Further describing my invention with reference to the drawings: 1 represents a fast 40 moving or feeding roll, which is suitably journaled and is driven by the gear 2. The said roll is provided with any desired number of corrugations or cutting edges 3, separated from each other by longitudinal 45 grooves 4, extending from end to end of the roll in lines parallel with the axis of the roll. The said corrugations are rounded or U-shaped at the bottom, thereby giving the corrugations very thin blades and sharp cutting 50 edges. They should preferably be forwardly inclined in the direction of their rotation, and the faces may be formed in the radial lines *a a*. The slow moving roll 5 is provided with a single corrugation 6, 6', 6'', 55 etc., extending in a continuous helix from end to end of the roll. This corrugation

is formed by means of a single groove or depression 7, 7', and 7''. This groove is also rounded or U-shaped in cross section, giving the helical corrugation a sharp edge and a 60 thin cutting body. It will be noted that in both the rolls this form of depression or groove provides an ample space within which the cut portions of material may be received in the process of cutting or cracking 65 without being crushed.

The fast moving roll shown in Fig. 4 has the grooves 10, 10', etc., slightly undercut, thereby providing something more of space within which the material when cut may be 70 received and also giving the cutting knives 11, 11', etc., a more distinctly forward inclination than is provided in Fig. 2. It will be noted that while the corrugations shown in Fig. 2 have the forward faces practically 75 on the radial line of the rolls, those in Fig. 4 at the bottom are continued backwardly from the radial line. But in either form a very sharp cutting edge is formed and set at an angle adapted best to strike and cut the 80 kernels of grain when presented to their action. Sharp clean cuts are produced on opposite sides of the grains by the action of the knives or corrugations on the slow roll. The kernels are cut into distinct fragments 85 producing little or no fine meal. And such fragments are received with the roomy grooves between the knives without pressure sufficient materially to break or crush them.

The corrugations of the slow moving roll 90 are shown as produced by a single helical groove extending from end to end thereof. This makes a simple automatic machine operation available in cutting or recutting the rolls. In like manner a plurality of helical 95 corrugations may be produced by a corresponding number of grooves. This, however, will increase the rapidity with which the corrugations advance and the angle of their inclination, and tend to produce a 100 crushing effect on the cut grains if carried too far. It will be noted, however, that, in the drawings, the grooves forming the corrugations are represented as much wider, and the rolls themselves as of much less diameter than in actual practice. And the actual pitch of the helical knives or corrugations will be determined by the size of the rolls, the number of corrugations and the work to be performed.

I claim:

1. In cutting rolls the combination of a

fast roll provided with a multiplicity of sharp edged corrugations substantially parallel to the longitudinal axis of said roll separated from each other by rounded grooves, and a slow roll provided with sharp edged helical corrugations extended from end to end of the roll and separated from each other by rounded grooves.

2. In cutting rolls the combination of a fast roll provided with a multiplicity of sharp edged corrugations substantially parallel to its longitudinal axis forwardly inclined in the direction of their rotation and separated from each other by rounded grooves, and a slow roll provided with sharp edged helical corrugations extended from end to end of the roll and separated from each other by rounded grooves.

3. In cutting rolls the combination of a fast roll provided with a multiplicity of sharp edged corrugations and undercut substantially parallel to the longitudinal axis of said roll separated from each other by rounded grooves, and a slow roll provided with sharp edged helical corrugations extended from end to end of the roll and separated from each other by rounded grooves.

4. In cutting rolls the combination of a roll provided with sharp edged corrugations substantially parallel to its longitudinal axis and separated from each other by rounded grooves, and a roll provided with a substantially continuous sharp edged corrugation extended helically from end to end thereof and formed by a corresponding continuous groove rounded at the bottom.

5. In cutting rolls the combination of a roll provided with sharp edged corrugations substantially parallel to its longitudinal axis

forwardly inclined in the direction of their rotation and separated from each other by rounded grooves, and a roll provided with a substantially continuous sharp edged corrugation extended helically from end to end thereof and formed by a corresponding continuous groove rounded at the bottom. 45

6. In cutting rolls the combination of a roll provided with sharp edged corrugations substantially parallel to its longitudinal axis forwardly inclined and undercut in the direction of their rotation and separated from each other by rounded grooves, and a roll provided with a substantially continuous sharp edged corrugation extended helically from end to end thereof and formed by a corresponding continuous groove rounded at the bottom. 50

7. In cutting rolls the combination of a fast roll provided with a multiplicity of sharp edged corrugations substantially parallel to its longitudinal axis forwardly inclined in the direction of their rotation separated from each other by rounded grooves, and a slow roll provided with a sharp edged helical corrugation extended from end to end of the roll, each convolution of said corrugation being separated from the adjacent convolution by a groove rounded at the bottom. 60

In witness whereof, I have hereunto subscribed my name this 14th day of February, 1916, in the presence of two subscribing witnesses. 70

JULES LE PAGE.
